UNITED STATES PATENT OFFICE.

EDWARD BOOTE, OF EAST ORANGE, NEW JERSEY.

DESIGN FOR A PLATE OR SIMILAR ARTICLE.

SPECIFICATION forming part of Design No. 31,621, dated October 10, 1899.

Application filed August 24, 1899. Serial No. 728,378. Term of patent 3½ years.

To all whom it may concern:

Be it known that I, EDWARD BOOTE, a citizen of the United States, residing at East Orange, in the county of Essex and State of New Jersey, have invented and produced a new and original Design for a Plate or Similar Article, of which the following is a specification, reference being had to the accompanying drawing, forming a part thereof, which represents a decoration embodying the features of my design.

The leading features of the design consist in a series of scroll-stems in circular order, festoons of foliage and floral sprays draped 15 at the scroll-stems, and a circular panel in

which a chain of flowers, buds, and branches of the wild-rose type appear.

The minor features of the design consist in the border for the circular panel and a saw-tooth ornamentation for the border. 20

I claim—

The design for a plate or similar article herein shown and described.

In testimony whereof I have signed my name to this specification in the presence of 25 two subscribing witnesses.

EDWARD BOOTE.
